LUGGAGE BAG

Leslie Marshall, 15 Pine St., Woodmere, N.Y. 11598

Original design application Jan. 28, 1971, Ser. No. 21,123, now Patent No. 221,318, dated July 27, 1971. Divided and this application July 15, 1971, Ser. No. 163,116

Term of patent 14 years

Int. Cl. D3—01

U.S. CL. D87—5 G

FIG. 1

FIG. 2

FIG. 4

FIG. 3

FIG. 4

FIG. 1 is a front elevational view of a luggage bag showing my new design;

FIG. 2 is a top plan view;

FIG. 3 is a rear elevational view; and

FIG. 4 is a side elevational view.

This is a division of design application Ser. No. D. 21,123, filed Jan. 28, 1970, now Pat. D. 221,318 of July 27, 1971.

I claim:

The ornamental design for luggage bag, as shown and described.
